ULTRA HIGH FREQUENCY OSCILLATOR
SYSTEM

Clarence W. Hansell, Port Jefferson, N. Y., assignor to Radio Corporation of America, a corporation of Delaware

Application November 28, 1934, Serial No. 755,158

18 Claims. (Cl. 250—36)

This invention relates to high frequency oscillation generators.

For the purpose of generating oscillations having frequencies of the order of 300,000 kilocycles and higher, there have commonly been used such apparatus as the Barkhausen oscillator and the magnetron. The oscillations produced in these oscillators are obtained by a sort of whistle effect wherein the electrons themselves produce the oscillations without any control element for controlling the flow of electrons passing through the tube in the manner commonly employed in ordinary vacuum tubes. In the Barkhausen oscillator there is a pendulum or to-and-fro motion of the electrons about the grid at the center point, groups of these electrons being drawn from the cathode toward the grid and, after passing through the grid returning again to it, some of these electrons returning to the vicinity of the cathode. The electrons returning to the cathode build up a dynamic space charge in such manner as to control the emission from the cathode in much the same way as a negative charge on the grid controls the emission from the cathode of an ordinary vacuum tube. In considering the Barkhausen oscillator, it should be noted that a negative charge exists in the space by virtue only of the presence of the electrons themselves, since no control electrode is required. This phenomenon, it has been found, is much more successful in producing ultra high frequency oscillations than that employed in the ordinary vacuum tube wherein control electrodes are used, for the reason that the capacity current to the control electrode in the ordinary vacuum tube becomes so enormous that the losses due to this current prevent oscillations taking place at extremely high frequencies.

Both the Barkhausen and magnetron oscillators, however, are subject to limitations because there is a certain limiting voltage which it is practical to use for a given spacing of electrodes. When it is attempted to obtain higher and higher frequencies by increasing the voltage, a practical limit is soon reached beyond which any increase in voltage must be accompanied by an increase in electrode spacing, a matter which requires that the electrons travel over longer paths. Since an increase in the time of travel of the electrons causes a decrease in the oscillating frequency, a certain point is soon reached beyond which no further increase in frequency may be obtained by increasing the voltage, because of the necessity for the greater spacing between electrodes.

55 A primary object of the invention is to make it

possible to obtain relatively very high power by means of oscillators without a corresponding decrease in the limiting frequencies which may be produced, particularly in the case of oscillators functioning on the Barkhausen and magnetron principles.

An important feature of the present invention is the solid type of cylindrical plate electrode used, which has an aperture or slot therein for enabling groups of electrons to pass through the plate electrode to a positive charged anode spaced away from the plate and facing the aperture or slot.

Although the principles underlying the invention are described with special reference to magnetron and Barkhausen oscillators, it is to be distinctly understood that the invention is not limited thereto, nor to the particular arrangement of parts shown, since other organizations of parts can be used without departing from the spirit and scope thereof.

Referring to the drawing:

Fig. 1 illustrates diagrammatically, the invention as applied to a magnetron type of oscillation generator, and

Fig. 2 shows a Barkhausen oscillator system embodying the features of the invention.

For the sake of simplicity and in order not to complicate the drawing, both figures show cross sectional views of the oscillator tubes.

Fig. 1 illustrates, in general, an ultra short wave oscillation generator in the form of a magnetron having, within an envelope 1, a cylindrical plate electrode 2; a cathode 3 extending along the longitudinal axis of the plate cylinder, the whole being surrounded by a field coil 4 for producing an intense magnetic field in a direction parallel to the axis of the filament. Since the method by which oscillations are produced in magnetrons is well known, and is adequately described in Japanese Patent No. 75,255, granted January 25, 1923, to Kinjirō Okabe, and in my United States Patents Nos. 2,037,897 and 2,041,830, granted April 21 and May 26, 1936, respectively, it will not be described herein.

According to the present invention, the cylindrical plate 2 of the magnetron is provided with a slot 5, and facing this slot there is provided, within the envelope 1, an anode 6 which is maintained at a very high positive potential by source 7; whereby during the operation of the magnetron and while oscillations are being produced, those portions of the electrons which approach the area of the slot 5 and come within the electrostatic field of the anode 6 will be drawn to

ward the anode 6. In this manner groups or puffs of electrons are emitted through the slot and accelerated toward the anode 6, which groups of electrons constitute a fluctuating current having a frequency equal to the frequency of oscillations being produced by the magnetron oscillator.

Since the magnetic field causes the electrons to take a curved path, anode 6 is made sufficiently large to extend to one side of the aperture so that the electrons do not miss it altogether. If desired, the anode may be positioned on one side of the aperture a suitable amount, as shown in Fig. 2, and not directly opposite the aperture.

15 Although it is preferred to use a slot in the plate 6, it will be quite evident that any suitable aperture having appreciable size will function as well.

As an illustration of the amount of power capable of being obtained by the oscillator of the invention, let it be assumed that the plate 2 of the magnetron oscillator is maintained by source 7 at a positive potential of 2000 volts, and anode 6 at approximately 100,000 volts relative to the 25 cathode. If the total plate current in the magnetron oscillator functioning to produce frequencies of the order of 1,000,000 kilocycles is approximately 0.5 ampere and the peak emission current permitted to escape through the slot in plate 2 is 0.1 ampere, then the R. M. S. value of the current through the slot to anode 6 will be approximately

$$0.1 \times \sqrt{2}/2 = 0.035 \text{ ampere}$$

35 The effective or R. M. S. alternating current voltage, available for internal drop and useful output to the output circuit connected to anode 6, will be

$$100,000 \times \sqrt{2}/2 = 35,000 \text{ volts}$$

40 If it is assumed that the anode 6 is 100% efficient then the output will be

$$0.035 \times 35,000 = 1225 \text{ watts}$$

45 In practice the anode 6 will be perhaps 40% efficient and provide an output of about 500 watts. The remaining power of about 625 watts will be lost in heat at the anode. It will be understood, of course, that the specific values herein mentioned are only given by way of example, since they happen to be approximately the values obtainable by types of magnetron oscillators commonly used in the field.

The anode circuit may, if desired, be tuned by 55 a condenser 8, one of whose plates is connected to a movable slider 9 arranged to glide over the connection extending from the anode 6 to the source of potential 7. Any suitable utilization circuit, such as an antenna 10, may be connected to the anode circuit through a transmission line 60 11, which in turn is shown inductively coupled to the anode circuit by means of a straight wire lead 12. If desired, tuning elements such as 65 trombone slides 13, 14 may be inserted in the transmission line circuit for tuning the line to the desired frequency. Telegraph key 15 is merely illustrative of any suitable means for modulating the oscillations produced.

Since radiation takes place directly from the 70 pulsating electron stream made up of the groups of electrons which are accelerated toward the anode 6, it is preferred to use a reflector 15 instead of the transmission line antenna output circuit. Thus, by allowing radiation to take 75 place directly from the electron stream there is

obtained a sort of infra-red lamp which may be used in the focus of the reflector 15, the latter being designed to reflect the radio frequency waves in much the same way as a reflector of light. By positioning the tube in the reflector 15 in any desired manner, advantage may be taken of the position for maximum radiation, although it will be noted that such maximum radiation from the pulsating stream of the electrons will not ordinarily be at right angles to the 10 axis of the tube.

Fig. 2 illustrates the application of the principles of the present invention to a Barkhausen oscillator. In this figure, the elements of the tube within the envelope are arranged similar to those 15 in Fig. 1 except for the provision of a grid 16 which is shown to be positively charged by source 7, while the plate 2 is negatively charged by source 17 in order to obtain the desired pendulum motion of the electrons. As shown in the drawing, anode 6 is maintained at a much higher positive potential than grid 16 relative to the cathode. Portions of the electrons emanating from the cathode 3 and passing through the grid 16 travel out to the vicinity of the plate 2, 25 some of which are subjected to the electrostatic field from the anode 6 in the same manner as the electrons of the magnetron oscillator of Fig. 1. In this case also, radiation may be directly obtained from the pulsating electron system 30 flowing to the anode 6, if desired, or the energy may be amplified in output circuit 17, shown coupled to the anode lead.

From the foregoing it will be quite apparent that the invention is applicable to various types 35 of oscillators such as the Gill-Morrell type of oscillator, and oscillators of the ordinary type wherein there is employed a vacuum tube of small dimensions capable of producing very high frequency oscillations in the same manner as low 40 frequency oscillations are produced with the ordinary vacuum tube.

What is claimed is:

1. An ultra high frequency oscillation generator comprising a cathode, a substantially cylindrical electrode surrounding said cathode and apertured to permit the passage of electrons therethrough, means including connecting circuits so related to said cathode and said electrode as to constitute therewith a self-contained oscillator, 45 an anode located outside said apertured electrode for receiving the electrons passing therethrough, and means including a source of potential for applying a positive potential to said anode for attracting electrons from said cathode toward said 50 apertured electrode, whereby electrons escaping through said apertured electrode impinge on said anode.

2. An ultra high frequency oscillation generator comprising a cathode, an imperforate, substantially cylindrical plate electrode having an aperture in the side thereof surrounding said cathode, means for attracting electrons from said cathode toward said plate electrode, and an anode located outside said plate electrode and facing 60 said aperture, means for producing electron oscillations within the hollow area of said plate electrode, and means for supplying a high positive potential to said anode with respect to said cathode for producing an electrostatic field in the 65 vicinity of said aperture, whereby electrons escaping therethrough impinge on said anode.

3. An ultra high frequency oscillation generator having within a single container a cathode, a metallic substantially cylindrical plate electrode 70

surrounding said cathode and having a slot running through the entire length thereof, an anode outside said cylinder but within said envelope facing said slot whereby electrons escaping therethrough impinge on said anode, means for producing electron oscillations within the hollow area of said cylindrical plate electrode including a source of potential for applying a positive potential on said plate and a relatively very high positive potential on said anode with respect to said cathode.

4. An ultra high frequency oscillator comprising an envelope having within it a cathode and a substantially cylindrical plate electrode surrounding said cathode, said plate electrode having an aperture in the side thereof for the escape therethrough of electrons emanating from said cathode, and an anode located within said envelope and outside said plate electrode and directly in line with said aperture and cathode for receiving said electrons, means for maintaining said cylindrical plate at a positive potential and said anode at a much higher positive potential relative to said cathode, and a field coil surrounding said envelope for influencing the direction of travel of said electrons.

5. An electron discharge device comprising a cathode, a grid, and a cylindrical plate, means for supplying said grid with a high positive potential and said plate with a much lower potential relative to said cathode, said plate having an aperture for the escape of electrons therethrough emanating from said cathode and passing through said grid, and an anode facing said aperture for receiving said electrons after their escape through the aperture of said plate, and means for maintaining said anode at a positive potential which is much higher than that applied to said grid.

6. In combination, an ultra high frequency oscillation generator comprising a cathode, an imperforate, substantially cylindrical plate electrode surrounding said cathode, said plate electrode having an aperture in the side thereof, means for attracting electrons from said cathode toward said plate electrode, means for producing oscillations within the hollow area of said cylindrical plate electrode, and an anode located outside said plate electrode and facing said aperture whereby electrons escaping therethrough impinge on said anode, a source of potential in circuit with said cathode and a connection from the positive terminal of said source to said anode, a tuning reactance conductively connected to said connection for tuning the oscillations in said anode circuit, and a utilization device coupled to said connection.

7. An ultra high frequency oscillation generator comprising a cathode, an imperforate, substantially cylindrical plate electrode surrounding said cathode substantially completely, said cylindrical plate having an aperture in the side thereof, means for attracting electrons from said cathode toward said plate electrode, means for producing electron oscillations within the hollow area of said plate electrode, and an anode located outside said plate electrode and facing said aperture, said anode being positively biased whereby electrons escaping through said aperture impinge on said anode.

8. An ultra high frequency oscillation generator comprising a cathode, a hollow, imperforate plate electrode substantially completely surrounding a portion of said cathode, said plate having an aperture in the side thereof, means including a source of potential for attracting electrons from

said cathode toward said plate electrode, means for producing electron oscillations within the hollow area of said plate electrode, an anode located outside said plate electrode and facing said aperture, and a connection from said anode to a positive terminal of said source whereby electrons escaping through said aperture are caused to impinge on said anode. 5

9. An electron discharge tube circuit comprising an electron emitting means, an anode, means for impressing a positive potential on said anode relatively to said emitting means, and means for causing an intermittent flow of electrons from said emitting means to said anode comprising additional electrodes and connecting circuits so related to said emitting means as to constitute therewith a braking field type of oscillator, said positive potential being such that the oscillatory energy available between said anode and said emitting means is large as compared with the 20 braking field oscillatory energy.

10. An electron discharge tube circuit comprising, an electron emitting means, an anode separated from said emitting means only by etheric space, means for impressing a positive potential 25 on said anode relatively to said emitting means, and means for causing an intermittent flow of electrons from said emitting means to said anode comprising additional electrodes and connecting circuits so related to said emitting means as to 30 constitute therewith a braking field type of oscillator, said positive potential being such that the oscillatory energy available between said anode and said emitting means is large as compared with the braking field oscillator energy. 35

11. An electron discharge tube circuit comprising, an electron emitting means, means for causing an intermittent flow of electrons from said emitting means comprising additional electrodes and connecting circuits so related to said emitting 40 means as to constitute therewith a braking field type of oscillator, an anode, and means for impressing a positive potential on said anode relatively to said braking field oscillator electrodes, said positive potential being such that the 45 oscillatory energy available between said anode and said emitting means is large as compared with the braking field oscillator energy.

12. An electron discharge tube circuit comprising an electron emitting means, an anode, means for impressing a positive potential on said anode relatively to said emitting means, and means for causing an intermittent flow of electrons from said emitting means to said anode comprising additional electrodes and connecting circuits so 55 related to said emitting means as to constitute therewith a self-contained positive grid triode oscillator, said positive potential being large as compared with the potentials used in said self-contained oscillator. 60

13. An electron discharge tube oscillator circuit comprising, an electron emitting cathode, an anode, means for impressing a positive potential on said anode relatively to said cathode, a tuned circuit connected to said cathode and anode, and 65 means for periodically impulsively energizing said tuned circuit from said potential impressing means comprising additional electrodes and circuit means so related to said cathode as to constitute therewith a self-contained positive grid 70 triode oscillator, said positive potential being large as compared with the potentials used in said self-contained oscillator.

14. The oscillator circuit as specified in claim 13 in which said energizing means comprises said 75

additional electrodes and circuit means adapted to cooperate with said cathode to constitute therewith a braking field type of oscillator circuit.

15. An electron discharge tube circuit comprising, an electron emitting means, an anode separated from said emitting means only by etheric space, means for impressing a positive potential on said anode relatively to said emitting means, and means for causing an intermittent flow of electrons from said emitting means to said anode comprising additional electrodes and connecting circuits so related to said emitting means as to constitute therewith a self-contained positive grid triode oscillator, said positive potential being large as compared with the potentials used in said self-contained oscillator.

16. An electron discharge tube circuit comprising, an electron emitting means, an anode, means for causing an intermittent flow of electrons from said emitting means to said anode comprising additional electrodes and connecting circuits so related to said emitting means as to constitute therewith a self-contained positive grid triode

oscillator, and means for impressing a positive potential on said anode relatively to the intermittent electron flow means constituted by said oscillator electrodes, said positive potential being large as compared with the potentials used in said self-contained oscillator. 5

17. The oscillator circuit specified in claim 13 in which said tuned circuit is adjusted so that the whole circuit including said tuned circuit and the interelectrode capacitances of the electron discharge tube is tuned to the frequency of said periodic impulses. 10

18. The oscillator circuit specified in claim 13, in which said energizing means comprises said additional electrodes and circuit means so related to said cathode as to constitute therewith a braking field oscillator circuit and in which said tuned circuit is adjusted so that the whole circuit including said tuned circuit and the interelectrode capacitances of the electron discharge tube 15 is tuned to the frequency of said periodic impulses. 20
